UNITED STATES PATENT OFFICE.

GEORGE F. HIAMS, OF TROY, NEW YORK.

SPRING-MATTRESS.

SPECIFICATION forming part of Letters Patent No. 270,799, dated January 16, 1883.

Application filed September 1, 1882. (No model.)

To all whom it may concern:

Be it known that I, GEORGE F. HIAMS, a citizen of the United States, residing at the city of Troy, in the county of Rensselaer and State of New York, have invented a new and useful Improvement in Spring-Mattresses for Beds, of which the following is a specification.

My invention relates to improvements in spring-mattresses for beds; and the object of my improvement is to provide a durable and cheap mode of fastening and sustaining the double springs to strips of hoop-iron or other metallic material, having at intervals elongated perforations or openings therein to receive such springs, or, by the use of wire or small rods twisted together, leaving at intervals elongated openings therein, into which such springs may be inserted and the parts fastened together by swaging, so as to hold said springs firmly therein. Said metallic supporting-pieces are fastened to a frame at their ends, to which frame the outer half-springs are attached. I attain the object sought by the mechanism illustrated in the accompanying drawings, in which—

Figure 1 is a view in perspective, showing a portion of a mattress covered with ticking or canvas, and a portion thereof showing the location and arrangement of the frame, springs, and metallic supporting-pieces to which the double or central springs are attached. Fig. 2 is a vertical view, showing a central or double spring and its attachment to the metallic strip or supporting-piece, also the attachment of said metallic strip or supporting-piece to the wooden frame, also the half or outer springs and their attachment to said frame, and a portion of such frame. Fig. 3 is a vertical view of a central or double spring, showing the form in which such springs are coiled so as to admit of the insertion of said springs into the apertures in said strips of hoop-iron or metallic supporting-pieces. Fig. 4 is an enlarged view of a portion of a supporting-piece of hoop iron, which is to support and hold the double springs, showing elongated perforations therein, which are to receive the central portion of said double springs. Fig. 5 is a view of a part of a metallic supporting-piece composed of three strands of wire or rods twisted together, leaving elongated openings therein for receiving

and holding therein the said central or double springs.

Similar letters refer to similar parts throughout the several views.

I will now describe the manner of constructing my improved spring-mattress.

In Fig. 1, C is an oblong frame, preferably of wood, the size required for a mattress. The sides and ends of such frame should be about three and one-half or four inches wide and about seven-eighths of an inch thick, and halved or doweled together at the corners. Such corners should be rounded, as shown in Fig. 1.

The supporting-pieces c in Figs. 2 and 4 are of hoop-iron about one-sixteenth of an inch thick and about seven-eighths of an inch wide, and long enough to extend onto the frame at each end about two and one-half inches, and should be bent at each end about one-half the thickness of the frame, as shown in Figs. 2 and 4, or so formed as to lie on a line with the center of the frame. Said pieces c have holes f near the ends, through which screws are put to fasten said pieces c to the frame at such distances as the double springs a are required to be placed on the supporting-pieces c. Said pieces are cut or punched so as to be in three or more parts, as at d d and e, Figs. 2 and 4. The length of these cuts should be a little more than the outer diameter of the double springs a at x, Figs. 2 and 3. The parts d d and e should be bent, so that the springs a at x can be passed between the parts d d and e, as shown in Fig. 2. The double springs a should be formed so that the two center coils will be close together, as shown at x, Figs. 2 and 3. To fasten together the supporting-pieces c and double springs a, pass that coil of said spring at x between the parts d d and e of the piece c, as shown in Fig. 2; then swage the parts together close to the wire of the spring, as shown in Fig. 2. This will hold said springs firmly in said piece c. Then fasten the supporting-piece c to the wooden frame C, as shown at f, Figs. 1 and 2. The half-springs b are made in the usual way, having a small portion of such springs at the smallest part of the coil bent so as to enter the hole in the piece c, which is near the screw-hole f, or into the frame C, where there is no metal piece, or piece c. Then a

small staple or hook, *h*, is driven into the frame *C* over and onto the springs, as shown in Fig. 2.

The metallic supporting-piece *c* may be made by twisting together three or more strands of wire, or three or more small rods, leaving un-twisted spaces to receive the springs *a* between the three strands, as shown in Fig. 5, and fastened therein by swaging, as described for hoop-iron, said twisted pieces *c* to be fastened 10 to the frame *C* with screws, as shown in Fig. 5, or in any desired manner.

The supporting-pieces *c* may be of any desired metal, or of any desired shape, and the places for holding the springs *a* may have three 15 or more parts or strands.

After all of the springs and supporting-pieces are fastened to the frame *C* the springs are fastened together and to the frame, in the usual manner, with twine or cord, and hoops *B*, 20 of rattan, are fastened to the outer part of the springs *b* in the usual way, and covered with burlaps or canvas, and padded and covered with ticking *A*, in the usual way.

I am aware that spring-mattresses have been 25 made in various ways, and springs fastened to frames, and central springs fastened to webbing. I therefore do not claim such combinations; but

What I do claim as my invention, and desire to secure by Letters Patent, is—

1. The metallic flat supporting-pieces *c*, fastened near their ends to the frame *C*, such pieces *c* being perforated at intervals, thereby forming three or more parts at said intervals, the double springs *a* being inserted (at their smallest diameter) between said parts and swaged firmly onto the wires of said springs, substantially as and for the purposes described and set forth. 35

2. The supporting-pieces *c*, fastened near 40 their ends to the frame *C*, such pieces *c* formed by twisting together three or more strands of wire or small rods, leaving at intervals spaces un-twisted, into said spaces the double springs *a* being inserted between the said strands, and 45 fastened therein by swaging the said parts firmly to the wire of said springs, substantially as described and set forth.

3. In a mattress, the combination of the frame *C* with the metallic supporting-pieces *c*, 50 the double springs *a*, and the half-springs *b*, arranged and constructed substantially as and for the purposes described and set forth.

GEORGE F. HIAMS.
